UNITED STATES PATENT OFFICE

118,831

DESIGN FOR A COMBINATION ICE CHIPPER AND BOTTLE BREAKER OR SIMILAR ARTI- CLE

Frank B. Norris, Shelby, Ind.

Application January 25, 1939, Serial No. 82,587

Term of patent 7 years

To all whom it may concern:

Be it known that I, Frank B. Norris, a citizen of the United States and a resident of the city of Shelby, in the county of Lake and State of Indiana, have invented a new, original, and ornamental Design for a Combination Ice Chipper and Bottle Breaker or Similar Article, of which the following is a specification, reference being had to the accompanying drawing, forming a part thereof.

On the drawing:

Figure 1 is a front elevational view of the combination ice chipper and bottle breaker showing my new design.

Figure 2 is a rear elevational view, and
Figure 3 is a side elevational view thereof.

The characteristic feature of the design resides in a combination ice chipper and bottle breaker consisting of a solid, one-piece stem or rod, offset at about its middle to provide a portion of less diameter, said last-mentioned portion being flattened gradually to a point at its end to provide the chipper, all as shown.

I claim:

The ornamental design for a combination ice chipper and bottle breaker or similar article as shown and described.

FRANK B. NORRIS.
